DISPENSING MACHINE

Isidor I. Gisser, New York, N. Y.

Application December 10, 1931
Serial No. 580,194

6 Claims. (Cl. 83—18)

This invention relates to improvements in dispensing machines and has particular reference to a machine for selectively dispensing various predetermined quantities of granular or pulverized commodities.

A feature of the invention is to provide a dispensing machine which is coin controlled so as to render the same suitable for installation in stores of the self service system.

Another feature resides in a coin controlled vending machine especially constructed for the dispensing of coffee, wherein predetermined amounts of coffee beans may be released into a grinder and ground or pulverized coffee dispersed into a bag or container. The releasing and grinding operation being automatically performed after the depositing of a coin into the coin mechanism and the subsequent manual operation of a knob to set the various mechanisms for operation.

A still further feature of the invention is the provision of a coin controlled vending machine which may be installed in grocery and delicatessen stores for dispensing various kinds of granular or pulverized commodities without requiring the services of a clerk, whereby the customer may operate the machine and expedite the service rendered by the establishment.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a front elevational view of my improved vending machine.

Figure 2 is a vertical sectional view therethrough.

Figure 3 is a view similar to Figure 2, but taken forwardly of the same.

Figure 4 is a vertical transverse sectional view on the line 4—4 of Figure 1.

Figure 5 is an enlarged detail vertical sectional view on the line 5—5 of Figure 3.

Figure 6 is a detail vertical sectional view on the line 6—6 of Figure 5.

Figure 7 is a detail perspective view of the solenoid circuit controlling switch.

Figure 8 is a detail front elevational view of the manual control switch.

Figure 9 is a detail horizontal sectional view on the line 9—9 of Figure 5.

Figure 10 is a diagrammatic view of the elec-

tric circuits which control the actuation of various mechanisms.

Referring to the drawings by reference characters, the numeral 10 designates a housing or casing which is designed to resemble a house or building, the top of which is provided with a peaked roof, one side of the roof constituting a door or cover 11 hinged to one of the side walls of the casing as at 12. Suitable catch means 13 is provided for securing the cover 11 in closed position. By opening the door or cover 11, access may be had to the inside of the casing when it is necessary to adjust or repair any of the working parts contained therein.

Mounted within the casing 10 adjacent the top thereof is a hopper 14, the same being provided with a plurality of outlets 15 in the bottom thereof, and the said bottom is formed of such shape as to cause the contents of the hopper to gravitate toward the respective outlet openings 15. The hopper 14 communicates with a filling spout 16 which is in the shape of a chimney extending from the roof of the casing, and the top of the spout is normally closed by a door or hinged cover 17. It is through the spout 16 that the hopper 14 may be filled with the commodity to be dispensed, and in this instance we shall assume that the hopper contains coffee beans 18.

Mounted in sleeve bearings 19 disposed directly beneath the respective outlets 15 are cylindrical measuring members 20, the diameters of which vary to permit of the dispensing of predetermined quantities of the contents of the hopper 14. For instance, the central cylinder 20 may be of a size to receive one pound of coffee beans, while the next smaller cylinder may receive and dispense one half pound, and the third cylinder receive and dispense one quarter pound. Each of the cylinders 20 is provided with an elongated slot 21 in the peripheral wall thereof for normally registering with the respective outlets 15 of the hopper, and at which time the cylindrical member may be set in filling or receiving position. Leading from the bottoms of the respective bearing sleeves 19 are branch chutes 22 which communicate with a common outlet chute or tube 23, and the lower end of this tube enters the inlet 24 of an electric coffee grinder 25 which rests upon the bottom of the casing and includes an electric motor 26. The grinder 25 also includes a discharge spout 27 which extends forwardly toward the front wall 28 of the casing where it connects with the upper end of a discharge or outlet chute 29. The top wall of the

outlet chute 29 is provided with a glass transparent window 30, while the lower open end is closed by a hinged door 31. The door 31 normally closes the discharge chute to permit the commodity to be dispensed to back up in the chute which may be viewed by the customer through the window 30, and when it is seen that the chute is substantially filled, the door may be swung to an open position to allow the coffee or other commodity to be discharged therefrom into a bag or container placed beneath the open end of the chute.

Each of the cylindrical measuring members 20 is mounted in the same manner, and is controlled by identical and individual mechanisms, so that a description of one will suffice for the other. Extending axially from opposite ends of each cylinder are hubs 32 and extending forwardly from the front hub is a stub shaft 33 in which the hub is keyed by a set screw or the like. Extending from the other hub 32 rearwardly of the cylinder is a stub shaft 34 keyed to that particular hub by a set screw or other suitable element. The hubs 32 are journaled in opposite walls of the hopper as best seen in Figure 5 of the drawings.

Fixed to the forward end of the stub shaft 33 is a coin receiver 35, which is rotatably mounted in a ring-like casing 36 mounted in a vertically disposed coin chute 37. The top of the coin chute 37 opens through the front wall 28 of the casing as at 38, while the lower end of the chute extends into a coin box 39 mounted within the casing and to which access may be had through a door 40 swingable through an opening provided in one of the side walls of the casing 10. All of the chutes 37 of the various individual coin controlled mechanisms lead to the common coin box 39 as will be seen by reference to Figure 3 of the drawings.

The body of the coin receiver 35 is provided with a slot 42 adapted to be brought into registration with the coin chute 37 on opposite sides of the ring like casing 36, the said casing being provided with a coin inlet 43 and a coin outlet 44. Pivottally mounted between the walls of the slot 42 is a bell crank lever 45, the vertical arm of which is engaged by a pivoted dog 46 which is normally disposed in the path of the coin as it enters the slot 42 from the upper branch of the coin chute 37. The horizontal arm of the bell crank 45 is bent at right angles into a finger 47 which enters the outlet slot 44 in the ring like casing 36 when the coin mechanism is set for the reception of a coin to operate the same. Pivoted to the vertical arm of the bell crank lever is a key or latch arm 48, the free end of which is provided with a flat head 49 slidable into a bore 50 provided in the front end of the body of the coin receiver 35 when the latch arm is extended but which head 49 is retracted from its position within the bore 50 upon movement of the bell crank lever to the dotted position which action occurs when the coin inserted into the coin slot is received in the receiver 35. It will also be noted that when the coin strikes the dog 46 to actuate the bell crank lever, the finger 47 will be moved to a plane within the inner walls of the ring like casing 36 so as to ride against the wall during rotation of the carrier in a manner to be hereinafter explained.

Mounted on the front wall 28 of the casing 10 in axial alignment with each cylindrical measuring member is a manually operated switch 51 which in front elevation resembles a radio dial.

The switch comprises a casing 52 mounted in the front wall 28, a dial plate 53 containing indicia to indicate when the switch is turned on and off, and a rotatable shaft 54 which is disposed in axial alignment with the bore 50 of the coin receiver 35. The inner end of the shaft carries a collar 55 which is provided with a slot or bifurcation 56 into which the flat head 49 of the key lever extends for the purpose of preventing rotation of the shaft until a coin has been deposited into the chute 37 and is received in the coin receiver 35. The outer end of the shaft 54 of the switch carries a manipulating knob 57, while fixed to the shaft within the casing is a contact arm 58 which is adapted to be brought into bridging engagement with a pair of electric contacts 59 when the switch is in an "on" position. This switch is of the usual snap type wherein one quarter revolution of the knob will cause the switch to be turned on and another quarter turn will effect the turning off of the same. The key or latch lever 48 tends to normally lock the switch against operation, but upon actuation of the latch mechanism by the coin, the knob is free to be turned in order to turn the switch to "on" and "off" positions.

Journaled in a panel 60 of insulating material mounted rearwardly of the battery of measuring cylinders is a stub shaft 61 disposed in axial alignment with the stub shaft 34, the forward end of the stub shaft 61 being provided with a socket 62 for receiving the rearwardly extending end of the stub shaft 34 while a set screw 63 fixedly secures the stub shaft 61 to the stub shaft 34. Fixedly mounted on the stub shaft 61 is a ratchet wheel 64 having two diametrically opposed notches 65 in the peripheral edge thereof. Freely mounted on the shaft 61 and disposed against the ratchet wheel is a disc 65' which is of a diameter larger than the diameter of the ratchet wheel and which carries a pivoted pawl 66 which is urged in the direction of the periphery of the wheel by a flat spring 67 so as to cause the pawl to enter the notches as the disc 65' rotates in the manner hereinafter to be explained. Fixed to the disc 65' and also freely mounted on the shaft 61 is a gear 68 which is engaged by a vertically sliding rack bar 69 which constitutes the sliding core of an electric solenoid 70. The energizing of the solenoid 70 causes the downward movement of the rack bar 69 which in turn rotates the loose gear 68 and imparts rotation to the stub shaft 61 through the pawl 66 and ratchet wheel 64. Fixed to the stub shaft 61 are contact discs 71 and 72, the former having a notch 73 in the periphery thereof, while the contact disc 72 is provided with a like notch 74 but oppositely disposed with respect to the notch 73 as will be seen in Figure 7 of the drawings. The discs 71 and 72 are held spaced by a spacer nut 75 which is threaded to the rear end of the stub shaft 61 while a similar nut 75 spaces the disc 71 from the gear 68. The nut 76 is threaded on the stub shaft 61 and bears against the disc 72, while fixed to the extreme rear end of the stub shaft 61 is a sprocket wheel 77. A sprocket chain 78 passes around the sprocket wheel 77 and also around a larger sprocket wheel 79 carried by the outer end of the rotatable shaft 80 of the mechanically operated switch 81 which switch is mounted on the panel 60 below the solenoid 70.

Spaced flexible spring contacts 82 and 83 respectively bear against the periphery of the discs 71 and 72.

71 and 72 and are arranged in electric circuits presently to be explained.

By reference to Figure 10 of the drawings it will be seen that a wire 84 leads from the positive side of the battery or source of electrical energy and is connected to the switch arm 58 of each of the hand operated switches 51. The contact 59 of each switch is connected to one of the spring contacts 82 by a wire 85, while the shaft 61 is connected by a wire 86 to the solenoid 70 of each operating mechanism. A wire 91 leads from the solenoid 70 to the negative side of the source of electric energy whereby one solenoid operating circuit A is provided. It will be seen that when this circuit is closed by engagement of the switch arm 58 with the contact 59 that the circuit will be closed and the solenoid energized to actuate the rack bar 69 which will in turn impart a one half revolution to the measuring cylinder 20, but only after a coin of the proper denomination has been deposited in the coin slot so as to release the coin lock mechanism to enable the switch 51 to be operated. This operation of the rack bar in addition to moving the dispensing cylinder from a receiving to an emptying position also turns on the switch 81 through the sprocket 78 and sprocket wheels 77 and 79. The switch 81 includes a rotatable switch arm 88 which when in an "on" position bridges spaced contacts 89 and 90, and which contacts are arranged in an electric circuit 91 with the electric motor 26 of the coffee grinder 25. From the description of the diagram thus far, the solenoid has been energized to turn the dispensing cylinder a one-half revolution to cause the opening 21 to move into registration with the chute 22 so that the contents of the cylinder is deposited into the grinder 25, and the grinder circuit 91 has been closed by movement of the switch arm 88 into contacting engagement with the contacts 89 and 90. Thus it will be seen that the coffee entering the grinder in bean form may be ground, and during the grinding operation, the powdered or pulverized coffee passes into the discharge chute 29 from where it may be released through the opening of the door 31.

After the coffee dispensed from the measuring cylinder has been ground, the operator again turns the switch 51 so as to move the same to an "off" position whereupon the contact arm 58 engages the contact 92 also arranged in the hand switch 51. The wire 93 leads from the contact 92 to the spring contact 83 which after the initial operation of the hand switch is in contact with the periphery of the disc 72 and which with the wire 86, solenoid 70, and wire 87 constitutes a second solenoid circuit B. Thus it will be seen that the solenoid may again be actuated to move the rack bar 69 downwardly to again impart a one-half revolution to the measuring cylinder. It might here be stated that after the deenergizing of the solenoid 70 which occurs when the notch 73 causes a break between the contact arm 82 and disc 71, a spring 94 which is connected to the top of the rack bar and to a fixed part of the casing serves to return the rack bar to raised position and which action takes place without imparting rotation to the shaft 61, due to the ratchet wheel 64 and spring pressed dog 66. When the solenoid circuit B is closed, the solenoid actuates the mechanism to return the cylinder 20 to normal position and during such movement, the sprocket wheels 77 and 79 and sprocket chain 78 turns the switch 81 to an "off" position. The parts are now in their original position for

operation upon the insertion of another coin into the machine.

The above described operation of course occurs after a coin has been deposited, and reaches the coin receiver 35 and during rotation of the cylinder from its receiving to its emptying position, the coin remains in the receiver, but as soon as the cylinder has turned one half revolution, the said coin will be released through the outlet slot 44 from where it passes to the coin box 39.

From the foregoing description it will be seen that I have provided a coin controlled dispensing apparatus in which predetermined amounts of granular or powdered commodities may be dispensed, and in cases where the commodity is to be ground or pulverized such as in the case of coffee, means is provided for automatically setting the grinder into operation and for automatically rendering the grinder inoperative after the commodity has passed therethrough.

By reference to Figure 1 of the drawings, it will be seen that I have carried out the idea of a casing resembling a building or house by providing display windows 94 in the front thereof and behind which a holder 95 is positioned and 100 which holder is adapted to contain a quantity of the product to be dispensed. Also by reference to Figures 1 and 4, it will be seen that the front wall 28 adjacent the top has a clock 96 set therein so as to add to the attractive nature of the 105 device.

Having thus described the invention, what I claim as new and desire to secure by Letters Patent is:

1. In a vending machine, a hopper having a discharge outlet, a measuring cylinder rotatably mounted in said discharge outlet and normally in communication with the hopper, electrically operated actuating means for rotating said measuring cylinder, an electric circuit for said 115 actuating means, switch means normally locked and adapted to be unlocked for operatively controlling the electrically operated actuating means, coin operated means for unlocking said switch means for rendering the same operable, 120 an automatic stop means for disconnecting the actuating means circuit.

2. In a vending machine, a hopper having a discharge outlet, a measuring cylinder rotatably mounted in said discharge outlet and normally 125 in communication with the hopper, electrically operated actuating means for rotating said measuring cylinder, said electrically operated actuated means including a magnetically operated rack bar meshing with an idly rotatable pinion, ratchet mechanism connecting said pinion with said cylinder upon actuation of said rack bar in one direction and for permitting idle return of said rack bar upon movement of the same in an opposite direction, spring means acting upon said 130 rack bar to hold the same in an inoperative position, an electric circuit for said actuating means, switch means normally locked and adapted to be unlocked for operatively controlling the electrically operated actuating means, and automatic 140 stop means for disconnecting the actuating means circuit.

3. In a vending machine, a hopper having a discharge outlet, a measuring cylinder journaled for rotation within said discharge outlet and 145 having an opening therein normally in communication with said hopper, a shaft extending from one end of said measuring cylinder, a pinion gear loosely mounted on said shaft, an electro magnetically operated rack bar meshing with 150

said pinion gear, said electro magnetically operated rack bar including an actuating solenoid, spring means acting to normally hold said rack bar against the influence of the solenoid when energized, ratchet means between said shaft and said pinion for imparting rotation to said cylinder upon energizing of said solenoid, and for permitting said pinion to idly rotate during the return movement of said rack bar upon deenergizing of said solenoid, an electric circuit in which said solenoid is operatively arranged including a source of electrical energy, a switch arranged in said circuit for closing the same upon each actuation thereof, and an automatic stop means for disconnecting said electric circuit.

4. In a vending machine, a hopper having a discharge outlet, a measuring cylinder journaled for rotation within said discharge outlet and having an opening therein normally in communication with said hopper, a shaft extending from one end of said measuring cylinder, a pinion gear loosely mounted on said shaft, an electro magnetically operated rack bar meshing with said pinion gear, said electro-magnetically operated rack bar including an actuating solenoid, spring means tending to normally hold said rack bar against the influence of the solenoid when energized, ratchet means between said shaft and said pinion gear for imparting rotation to said cylinder upon energizing of said solenoid and for permitting said pinion gear to idly rotate during the return of said rack bar upon deenergizing of said solenoid, a pair of normally open electric circuits in which said solenoid is arranged including a source of electrical energy, a double acting control switch normally locked and arranged in said circuit, coin operated means for unlocking said switch for rendering the same operable for simultaneously opening one circuit and closing the other circuit, and vice versa, and automatic stop means for breaking either circuit when closed by said switch after a one-half revolution of said cylinder.

5. A vending machine comprising a casing, a hopper within said casing, a discharge chute, a rotatable cylinder mounted in said casing and having an opening therein normally disposed in a

filling position to establish communication between said cylinder and said hopper but movable to an emptying position with the opening in register with said discharge chute, actuating mechanism normally locked and adapted to be unlocked for rotating said cylinder from its filling position to its emptying position, coin operated means for unlocking said actuating mechanism for rendering the same operable, manual control means for rotating said cylinder from an emptying to a filling position, an electric grinder arranged within said discharge chute through which any substance passing therethrough is adapted to pass, and automatic means operable upon movement of said cylinder to a discharging position for operating said electric grinder and for rendering said grinder inoperative upon movement of said cylinder to a filling position.

6. In a vending machine, a casing, a hopper mounted in said casing having an outlet, a measuring cylinder rotatably mounted in said casing and having an opening therein normally in registration with said outlet, electrically operated actuating means for rotating said measuring cylinder one-half revolution on each actuation thereof, an electric circuit for said actuating means, manually operated electric switch means normally locked and adapted to be unlocked for controlling the actuation of said electrically operated actuating means, coin operated means for unlocking said switch means for permitting the successive turning of said electric switch means to a single "on" and "off" position upon the insertion of a single coin thereinto, an electric grinder mounted in said casing and having an inlet and a discharge outlet, a chute for receiving the contents of said cylinder when moved to an emptying position after the first half revolution thereof, and being connected to said inlet, and electric control means for operating said electric grinder when said measuring cylinder is in emptying position with the opening therein in registration with said chute, and for rendering said electric grinder inoperative at all other times.
